(57) **CLAIM**

The ornamental design for a ball, as shown and described.

DESCRIPTION

FIG. 1 is a front view of a ball showing a first embodiment of my new design having six sections;

FIG. 2 is a side view thereof;

FIG. 3 is a top view thereof;

FIG. 4 is a plan view showing the first embodiment in an alternate, unassembled arrangement;

FIG. 5 is a front view of a second embodiment of my new design having twelve sections;

FIG. 6 is a side view thereof;

FIG. 7 is a top view thereof; and,

FIG. 8 is a plan view showing the second embodiment in an alternate, unassembled arrangement.

1 Claim, 8 Drawing Sheets
